UNITED STATES PATENT OFFICE.

RICHARD LANCASTER, OF GILFORD, NEW HAMPSHIRE.

DESIGN FOR A WEATHER-FORECASTING DEVICE.

60,101.

Specification for Design.

Patented Dec. 27, 1921.

Application filed August 4, 1921. Serial No. 489,881. Term of patent 7 years.

To all whom it may concern:

Be it known that I, RICHARD LANCASTER, a citizen of the United States, residing at Gilford, in the county of Belknap and State of New Hampshire, have invented a new, original, and ornamental Design for a Weather-Forecasting Device, of which the following is a specification, reference being had to the accompanying drawing, forming part thereof.

In the drawing Figure 1 is a perspective view of a weather forecasting device showing my new design and Fig. 2 is an edge view of the same.

I claim:

The ornamental design for a weather forecasting device, as shown.

RICHARD LANCASTER.
